DOOR

Robert Katz, Brooklyn, N. Y.

Application January 10, 1949, Serial No. 70,050

3 Claims. (Cl. 189—46)

1

This invention relates to a door construction and more particularly to a glass door construction in which the frame is made of metal.

The principal object of this invention is the provision of an improved tubular metal frame for glass doors, which may be cut to any desired size in accordance with individual requirements. Heretofore, door frames of this general character have been made in accordance with given sizes, and great difficulty has been experienced in accommodating these door frames to door jambs of other than stock sizes. In the present invention, the door frame comprises a plurality of stile and rail members which are fastened to each other, and these members may be cut to any suitable length. They may thereafter be assembled to provide door frames of required dimensions.

Another object of this invention is the provision of a tubular metal frame for glass doors of the character described, whose leading edge is provided with a bevel to provide for proper clearance between said leading edge and the door jamb.

Still another object of this invention is the provision of a door of the general character described, having a lock mounted in its leading edge, whose face lies flush with the bevel on said leading edge, thereby presenting a continuous beveled leading edge with all the advantages inherent therein.

Doors made of a glass plate are much in demand. It is desirable to have as much glass exposed as possible, and to have as little frame work or support for the glass as is consistent with strength and security. Hollow aluminum tubing has been used to support these large glass plates or panels, but it has been necessary, in the past, to weld together the stiles and rails which support the glass panel. The surface of the aluminum tubing is finishing as by anodizing, and when the tubing is cut to size and fabricated as the frame around a glass panel, it has been necessary to weld the stiles and rails together. This welding causes discoloration at the joint, and it has been found that even when the welding is done on the aluminum tubing before the finishing is done, there still results considerable discoloration at the joint. Hence, an object of the invention is to provide means for uniting the stiles and rails of a door without the necessity of welding or soldering.

A still further object of this invention is the provision of a door of the general character described, which may be made of aluminum tubing and which is provided with steel reinforcing members to enable said aluminum stiles and

2

rails to be bolted together tightly, without yielding or sagging, and thus eliminate the necessity of welding.

A preferred embodiment of this invention is shown in the accompanying drawings, in which:

Fig. 1 is a face view of one type of door incorporating the features of the present invention.

Fig. 2 is another face view of another type of door which incorporates the constructional features of this invention, the door frame being partly broken away to expose one of the fastening member thereof.

Fig. 3 is an enlarged fragmentary view of the upper part of one of said doors, showing, by means of dotted lines, how a fastening member is used to secure the two stile members of the door frame to the upper rail member thereof.

Fig. 4 is a detailed fragmentary view of one of the upper corners of said door frame looking downwardly therefrom, the frame being partly broken away, to reveal, in section, the details of the connecting means by which the top horizontal frame member or rail and one of the vertical frame members or stiles may be fastened together.

Fig. 5 is a side view of the structure shown in Fig. 4, said view being also partly broken away and partly in section.

Fig. 6 is an end view of the structure shown in Figs. 4 and 5, said view being also partly in section.

Fig. 7 is a cross-sectional view of one of the stile members and especially of the stile which constitutes the leading or free swinging edge of the door.

Fig. 8 is a fragmentary face view of said member.

Fig. 9 is a fragmentary horizontal section through the stile member which constitutes the leading edge of the door, and through the pane of glass which is supported thereby, and through the door jamb which it meets.

Fig. 10 is an enlarged fragmentary face view of said stile member showing a lock carried thereby.

Fig. 11 is a horizontal section on line 11—11 of Fig. 10.

Fig. 12 is an end view of one of the fastening clips by which the vertical and horizontal frame members are fastened together.

Fig. 13 is a fragmentary side view showing said clip.

Fig. 14 is an elevational view showing a pair of doors and illustrating a modification of the invention.

Figs. 15 and 16 are face views of glass panels

used in doors showing detail of corner construction.

Fig. 17 is a fragmentary sectional view through the top rail and connected stile showing method of securing the glass panel in the modification shown in Fig. 14.

Fig. 18 is a sectional view taken on line 18-18 of Fig. 17.

Fig. 19 is a view similar to Fig. 17, but showing a further modification.

It has above been stated that this invention relates primarily to glass doors having metal frames. In Fig. 1, one of such doors is shown, said door having two vertical frame members or stiles 20 and 21 respectively, connected to two horizontal frame members or rails 22 and 23, respectively. This door is mounted on a door jamb by conventional means such as hinges 25 shown in the drawing. A second type of door incorporating the features of this invention is shown in Fig. 2, and it will be seen that this door is provided with a pair of stiles 30 and 31 respectively, as well as with three rails 22, 23, and 34, respectively, said last-mentioned rail being positioned between the first two mentioned rails, although not necessarily equidistant from them. Like the first door, the door shown in Fig. 2 is hinged to the door jamb by means of hinges 25.

The cross-sectional view in Fig. 7 of the leading door frame member, to wit, stile 21, shows that the leading edge 40 thereof is beveled. The corresponding edge 41 of door jamb 42 is correspondingly beveled, thereby providing for adequate clearance between the door and the door jamb and also providing a snug fit between the two. Further reference to Fig. 7 will disclose the fact that this stile 21 comprises a tubular member, substantially rectangular in cross section (with the exception of the beveled edge above noted) and having an L-shaped glass-holding bead 44 formed thereon, on the side opposite the bevel. The cross-sectional view in Fig. 4 of stile 20 shows that this stile resembles stile 21 in every respect except that it has no beveled face. Stile 20 also has an L-shaped bead 44 which can be seen in Fig. 5.

Figs. 9 and 11 best show how the panel of glass 46 is held in place in the door frame. It has already been mentioned that bead 44 is used to hold the glass panel in place, and it will be noted that a channel-shaped member 47, fastened to the frame member by means of screws 48, cooperates with the L-shaped member to confine the glass panel. The L-shaped projection on the frame member abuts one side of the glass panel and the channel member abuts the opposite side. If gaskets are found to be desirable in this construction, they may be inserted in any suitable conventional manner.

While it has been indicated thus far that the L-shaped bead is formed on the stiles, it should be understood that the rails resemble the stiles in substantially every respect except that they need not be provided with a beveled face, although that, too, may be had if desired. Hence, it will be understood that the rails comprise tubular members, substantially rectangular in cross-section, and having L-shaped beads formed along one side thereof.

These tubular members, to wit, those comprising the stiles and rails of the door, may be made of extruded aluminum in mill lengths. They may then be cut to appropriate size, that is, to stock size or to given dimensions in accordance with given requirements.

Tie rods or bolts 50 are used to fasten the stile and rail members together. One tie rod is used for each rail; hence, two tie rods are required for the door shown in Fig. 1, and three for the door shown in Fig. 2. It has been indicated that aluminum is preferred for the door construction herein claimed, and it will be understood that special means are required to prevent the aluminum from bending or sagging under the stress and strain of the tie rods. The special means herein provided for this purpose comprise two members, a clip 51 and a strong metal washer 52, such as a washer made of steel. Clip 51 is a U-shaped member which is best seen in Fig. 4. In production this clip may simply comprise a section cut from a long U-shaped channel. Its yoke is provided with a centrally-extending hole 53 (Fig. 12), and a plurality of holes 54 formed in its corners. It is through these holes 54 that rivets 55 may be introduced to fasten said clips to the stiles of the door as is best shown in Figs. 4 and 5. The steel washer 52 may be mounted on the inside of each stile and it will be understood that said washer is provided with holes registering with the holes in the clip. The tie rod 50 is then inserted into each rail member and its two ends are brought through the holes in the clips and washers in the manner shown in Figs. 4 and 5. The ends of the tie rods are screw-threaded and they accommodate nuts 56 which bear against the steel washers. It is clear that when these nuts are tightened upon the tie rods, they will clamp the stiles to the rails. The legs of the clip tend to prevent buckling of the walls of the rails; and the yoke fastened to the stiles, together with the steel washer, prevent undue strain in the walls of the stiles.

It has been stated that rivets are used to fasten the clip to the stiles. Other fastening means such as bolts may be used to equal advantage, but rivets are preferred. The washers need not be fastened to the inside wall of the stiles except by the tie rod itself. These washers are provided with holes registering with the holes in the clips, however, to provide clearance for the heads of the rivets or other fastening members as shown in Figs. 4 and 5.

When a door such as that shown in Fig. 1 is assembled, little difficulty will be encountered in reaching the nut of the tie rod to tighten them against the washers. Access to these nuts may be had through the open ends of the stiles, as shown in Fig. 4. After the frame is assembled, these openings may be plugged up by means of plugs or plates 60 which are shaped to correspond with the shape of the opening in said stiles. In Fig. 5 a plug of this type is shown in the open end of one of said vertical frame members. This plug may be held in place in the frame members by any conventional means or methods such, for instance, as a press fit between its side edges and the walls of the frame member. It is shown in Fig. 5 to be resting on the washer 52, and this is an added means of positioning the plug in the frame member.

When, however, a door such as is shown in Fig. 2 of the drawing is assembled, difficulty would be encountered in gaining access to the middle tie rod, were it not for the provision of a hole 61 in the stile directly opposite said middle tie rod. This hole is made sufficiently large to insert the washer, the nut, and a wrench. When the nut is screwed tight upon the tie rod, the opening in the stile is plugged closed in the same manner as its two end openings are plugged. A plate cor-

responding in shape to the shape of the hole in said frame member is inserted therein and a press fit will usually be found sufficient to hold said plate in place in said hole.

Among the refinements of which the present invention is susceptible is the use of pads 65 formed at the inner corners of the tubular frame members into which clips 51 are inserted. These pads serve as guides for the clips; they keep them aligned with said tubular members; and they provide only a limited bearing area between said clips and said tubular members, thereby eliminating much of the friction that would otherwise be encountered between said clips and said tubular members.

It has above been stated that at least one of said tubular frame members, to wit, that stile which provides the leading edge of the door, has a beveled wall. When a lock is mounted in said stile, the face of the lock which lies along the leading edge of the door should itself be provided with a bevel to coincide with the bevel of the door frame itself. This bevel is provided in the lock 70 shown in Figs. 10 and 11. The lock proper is conventional in every respect but its face plate 71 lies at an angle relative thereto which conforms in every respect to the angle of the door frame bevel relative to the door frame. The manner in which the lock may be held in place in the door frame is best shown in Fig. 11. It will be noted in said figure that tapped socket members 73 are fastened to the inside wall of the tubular frame member directly opposite the opening in the leading edge of the door frame through which the lock is inserted. Screws 74 are then inserted through the face plate of the lock in conventional manner, and these screws are made to engage the tapped sockets 73, all as shown in said figure.

The invention thus far has been described with relation to those doors which have complete frames, that is, stiles and rails around all four sides of the glass panels. The same principles, however, may be utilized for glass doors bounded on three sides or even on two sides of the glass panel.

In Fig. 14, for instance, there is shown a pair of swinging doors, wherein the meeting edges of the doors have no stiles. In such case, the glass panels G are shaped somewhat as shown in Fig. 15, the upper and lower corners of the meeting edge of the panel being acutely notched as at 80 to receive correspondingly shaped clips 81 which are formed as plugs to fit snugly into the ends of upper and lower rails 22a. Clips 81 are provided with a threaded bore 82 to accommodate threaded end 83 of tie rod 52a. Resilient padding or packing material 84 is interposed between the hooked portion 85 of clip 81 and the notched corner 80 of the glass panel, as well as around the edge of glass G in the grooves of the rails and stile. It will thus be seen that means are provided for securely holding a glass panel in a three-sided frame to produce a strong and efficient door.

In Fig. 19, there is shown the application of the same general principle to a glass door panel having no stiles but being supported by only a top and bottom rail. In such case, the glass panel is notched in all four corners as shown in Fig. 16, the notches 80a and 80b being provided for engagement by the clips 81 and 86, respectively. The clip 86 has a rail plug 87 which snugly fits into the rail, the plug having a hole 88 through which the tie rod 50b extends, the nut 75

56b being threadedly engaged with the end of the tie rod and fitting within a counterbore 89 in the plug 87. A disc 90 may be secured to the plug 87 to serve as a closure for counterbore 89, as shown in Fig. 19.

10 It will be appreciated that the foregoing describes only preferred embodiments of this invention and that said embodiments may be modified in numerous ways within the scope of the present invention. Illustrative of one such modification is the use of an opaque door panel in place of the glass pane hereinabove described and shown in the drawing.

15 Having thus described my invention, what I claim as new and desire to secure by Letters Patent, is:

20 1. In a door frame construction of the character described, a pair of spaced tubular stiles fastened to a pair of spaced tubular rails, the fastening members comprising screw-threaded tie rods which extend through the rails and project into and terminate within the stiles, nuts being provided on the ends of said threaded tie rods to bolt said stiles to said rails, reinforcements 25 being provided to prevent buckling of said rails, said reinforcements comprising U-shaped clips which are fastened at their yokes to the stiles, their leg portions extending into the tubular rails and bearing against the inner walls thereof, large arcuate washers being provided between the nuts and the inner wall of said stiles, with the concave side of each washer confronting the inner wall of the respective stile whereby the force exerted by said nuts is communicated to the sides of said inner wall remote from said tie rods.

30 2. A frame construction in accordance with claim 1, in which one of said stiles is hingedly connected to one post of a door jamb, the other of said stiles being provided with a bevel along 35 its leading edge to cooperate with a bevel formed on the opposite post of the door jamb.

35 3. In a door frame construction having at least one tubular stile and a plurality of tubular rails, means for securing each rail to said stile in abutting engagement, the wall of said stile which abuts against the end of said rail having a hole just large enough for the passage of a tie rod therethrough, said securing means comprising a screw-threaded tie rod which extends from one 40 end of the rail through said hole and terminates within said stile, means to secure said tie rod within the rail axially thereof, a nut on the extending end of said tie rod within said stile to bolt together said stile and a rail, a U-shaped 45 clip fastened to the outer surface of a wall of said stile and extending into said rail and bearing against the inner walls of said rail, a large arcuate washer mounted on said tie rod between the nut and the inner wall of said stile, with its 50 concave side confronting said latter inner wall whereby the force exerted by the nut is communicated to the sides of said inner wall remote from said hole in said stile.

ROBERT KATZ.
